UNDERGARMENT FOR WOMEN

Mary A. Goodman, Hartford, Conn.

Application March 27, 1934, Serial No. 717,667

1 Claim. (Cl. 2--78)

The present invention relates to nether garments, and more particularly to women's drawers of the open type which may be in the form of a separate garment or embodied in a union suit or a combination garment.

An object of the invention is to provide a bifurcated nether garment which has an open crotch portion with covering or protecting means, and which does not increase the thicknesses of material, provide gathered portions or seams, or otherwise mar or interrupt the desired smooth and flat fitting of the garment about the hips.

Another object of the invention is to accomplish the desired results without the use of gores, inserts, fullness of material or other expedients used to close the crotch opening and which increase the bulk of the material in the crotch portion of the garment, and to do away with buttoning gores and other means imposing undesirable strains on the garment and which are unreliable in use.

To accomplish the above stated objects, the present invention provides a bifurcated nether garment with an open crotch portion, and without closure gores or the like, with the crotch opening terminating a substantial distance below the natural waist line, so as to leave a smooth form fitting waist and hip portion to the garment, and wherein the crotch opening at the back of the garment is normally closed or covered by a peculiarly positioned and constructed flap drop lying wholly below the waist and hip portions of the garment and which hangs from a point of attachment to the garment at the upper rear end of the crotch opening to a point sufficiently low to protect adjacent garments from contact with the wearer particularly when seated. The flap drop so suspended may be readily raised and folded to one side in the act of opening the garment, and will normally remain in closed and protecting position without the use of buttons or other fastening devices.

It is well known that the dress fashions of the present time require smooth and uninterrupted waist and hip portions with the least possible number of thicknesses of material in the hip portion. Chiefly on account of this requirement in dress nether garments of the open crotch type are more or less discarded and consequently their advantages are lost. According to the present invention, the hip portion of the garment may remain smooth and uninterrupted and of a single thickness if desired and at the same time the advantages of the open crotch may be had without

danger of contact of the outer garments with the body of the wearer.

With the foregoing and other objects in view, the invention will be more fully described herein-after, and will be more particularly pointed out in the claim appended hereto.

In the drawing, wherein like symbols refer to like or corresponding parts throughout the several views.

Figure 1 is a rear elevation of a nether garment in position on a figure and constructed and provided with a flap drop according to the present invention, and

Figure 2 is a like view with the flap drop raised, showing the suspension of the flap drop from its upper end only and showing the relative position of the crotch opening of the garment.

Referring now to the drawing, 10 designates the body of a nether garment which may be of any desired type, a single bifurcated garment, a union suit as shown or a combination garment embodying a bifurcated portion.

The garment 10 has a waist portion 11 which may conform to the natural waist of the wearer and which is disposed at the upper edge of a hip portion 12. The hip portion 12 may be one or more thicknesses of material and may be smooth and uninterrupted across the back of hips. This hip portion 12 extends for a considerable distance below the waist portion 11, such as seven inches in a medium sized garment. The garment has a pair of leg portions 13 which extend downwardly from the hip portion 12 and provide a crotch between the leg portions, and the garment is interrupted or left open at the crotch to provide a crotch opening 14. The crotch opening 14 may be of any suitable configuration and may have marginal gores or edgings if desired although the same are not required for closing and protecting the crotch opening.

The back of the garment 10 is covered or closed by a flap drop 15 which may be of the same material as that of which the garment 10 is made or may be of other material if desired. The flap drop 15 is preferably an inseparable part of the garment, but not necessarily so as other objects and advantages may accrue from a modification of the present disclosure.

The flap drop 15 is secured at its upper end 50 only to the garment 10, and this may be accomplished by one or more lines of stitching 16 extending horizontally across the bottom of the hip portion 12 at the back of the garment.

The crotch opening 14 terminates at its upper 55

end at the back of the garment 10, at or adjacent to the lines of stitching 16 so that the hip portion 12 is left smooth and uninterrupted. The flap drop 15 is suspended from the lines of stitching 16 at the back of the garment and over the crotch opening 14 to cover the same and protect the outer garments from contact with the body of the wearer. The flap drop 15 is of suitable length to fully cover the crotch opening 14 when the wearer is seated and is of sufficient width to overlap the leg portions 13 at opposite sides of the crotch opening 14 and insure full protection to the outer garments.

Preferably the flap drop 15 flares in width from its upper attached end to its lower end so that when the lower free end of the flap drop 15 is forced between the leg portions 13 to any appreciable extent, or the leg portions 13 be spread apart, the flap drop 15 will still cover the crotch opening 14 and afford the desired protection.

A reinforcing strip 17 is secured by the lines of stitching 16 across the upper end of the flap drop 15 and the bottom of the hip portion 12 of the garment 10 to reinforce the latter and prevent rupture at the top of the crotch opening 14. The strip 17 may be carried at opposite ends beyond the edges of the flap drop 15 to any desired extent for holding the hip portion 12 in shape and reinforcing all of the adjacent parts of the garment.

Various types of gores, aprons and flaps have been heretofore used but they are not adaptable to the bifurcated nether garment of the open crotch type as they add to the thickness and fullness of the hip and waist portions of the garment and otherwise increase the bulk and fullness of the garment. To obtain the combined advantages of this type of nether garment and the flap, the present invention relatively modifies both the garment and the flap so that the crotch opening 14 and the flap drop 15 do not extend into or above the hip portion 12 of the garment, with the result that additionally the hip portion 12 is left smooth, uninterrupted and free to conform to the hips of the wearer.

It will thus be seen that the present invention provides a woman's open drawers union suit or tri-set with a piece of goods or drop 15 of convenient width hung across the middle of the back about seven inches below the natural waist line 11 of a medium size garment 10 and falling to a suitable level above the knees, and provides a more satisfactory protection of other garments from contact with the body of the wearer and from soil resulting therefrom than is provided by the usual device of gores (overlapping and sometimes buttoned over) set into the legs of an open drawers union suit. Thus the garment may be made without overlapping leg gores; though gores may be used, if desired, provided that they do not give trouble by extending above the level of the top of the drop, or by overlapping each other too much at that level and thereby binding the opening. Buttoning over of gores, with its uncertainty and strain on the garment, is done away with in the present invention. If the material is itself not sufficiently elastic, the drop

may be made full across the top, or may be cut bias, or both, in order to avoid "pull" and strain on the garment.

The suspension of the flap drop 15 at its upper end only provides the necessary give between the garment and the flap drop 15 and avoids undue strain on the rest of the garment. The flap drop 15 may be made wholly or in part of elastic material to further insure the automatic adjustment of the drop 15 without subjecting the garment to undue strain.

In use, the coming together of the garment legs 13 at the top of the crotch opening 14, whether made with or without gores, should be at least seven inches below the natural waist line 11 on a medium size garment, so that the flap drop 15 can be set low, and bulk on the hip level be avoided. The flap drop 15 is stitched at 16 firmly across the middle of the back of the garment 10 with a band or strip 17 extended at each 20 end to distribute strain, and hangs down to a convenient level above the knees of the wearer, so that whether the wearer is sitting or standing, the flap drop 15 will cover the opening 14 between the legs 13 of the garment where, when 25 being worn, they tend to spread apart. The flap drop 15 hangs detached at the sides so that its position may be easily changed except at the top.

The flap drop 15 may be of any desired width, length, material and construction to adequately 30 cover the crotch opening 14 and carry out the objects of this invention, and the flap drop 15 may be secured across the back of the garment at any suitable distance below the waist 11 provided that the hip portion 12 is left free and uninterrupted to the desired distance below the waist 11, the lengths and other dimensions hereinbefore recited being by way of example only and being susceptible to change incident to various 35 conditions met with in style, use and construction. 40 The double line showing of the waist 11 is merely illustrative and diagrammatic to show the approximate natural waist line of the wearer and does not indicate any structural feature of the garment 10.

It is obvious that various changes and modifications may be made in the details of construction and design of the above specifically described embodiment of this invention without departing from the spirit thereof, such changes and modifications being restricted only by the scope of the 50 following claim.

What is claimed is:

A garment as set forth comprising a body having leg, waist and hip portions, said body in the 55 leg portions thereof having a crotch opening terminating at the rear of the garment at a point spaced downwardly from the upper edge of the waist portion and substantially coplanar with the top of the hip portion, an elongated narrow strip 60 extending horizontally of the body at the upper end of the rear of said crotch opening, stitching for securing said strip to the body, and a flap drop having its upper end interposed between said strip and the body and secured by said stitching, said drop at its upper end being narrower than the length of said strip.

MARY A. GOODMAN.
